UNIVERSAL ADJUSTABLE TOOLHOLDER DEVICE

Arnold Meyer, New York, N. Y.

Application March 18, 1952, Serial No. 18,948

Term of patent 14 years

(CL. D54—14)

To all whom it may concern:

Be it known that I, Arnold Meyer, a citizen of the United States of America, residing at New York, county and State of New York, have invented a new, original, and ornamental Design for a Universal Adjustable Toolholder Device, of which the following is a specification, reference being made to the accompanying drawing, forming part thereof.

Fig. 1 is a front-elevational view of the universal adjustable toolholder device, showing my new design;

Fig. 2 is a top plan view of the device of Fig. 1;

Fig. 3 is an end view of the device of Fig. 2 as seen from the right hand side.

The other end of the table portions, not shown, are substantially like those shown in Fig. 3.

The essential features of my design reside in the portions shown in full lines.

I claim:

The ornamental design for a universal adjustable tool holder device, substantially as shown and described.
